UNITED STATES PATENT OFFICE

2,024,053

CAR REFRIGERATION

David P. Minard, Chicago, Ill., assignor to Armour and Company, Chicago, Ill., a corporation of Illinois

Application November 9, 1934, Serial No. 752,364

28 Claims. (CL 62—171)

This invention relates to car refrigeration, the present application being in part a continuation of application for Letters Patent of the United States filed by me May 14, 1934, Serial No. 725,514.

5 The object of the invention is to provide a method of refrigerating cars by which the period of refrigeration is prolonged and the degree of refrigeration obtained is increased over the methods now commonly employed.

10 A further object of the invention is the provision of a method for the purpose indicated by which the air within the car is more uniformly treated and the refrigerating agent utilized to greater advantage than in the present methods.

15 The invention also aims to provide a method of car refrigeration by which greater economy in the costs of operation and in the cooling agents employed is attained.

20 As a further object of the invention the latter has in view the provision of a method that is adaptable to the refrigeration of cars, whether for maintaining the required low temperature conditions in transit or for pre-chilling the cars prior to forwarding the same, and wherein the refrigerating agent is maintained out of contact 25 with the car interior. Thus the interior is not adversely affected by circulating air laden with the refrigerating agent, and for the same reason the interior hardware of the car is much less likely to be adversely affected.

25 Other objects and advantages will appear as the nature of the improvements is better understood, the invention consisting in the novel method hereinafter described, illustrated in the accompanying drawings, and finally pointed out in the appended claims.

30 A preferred adaptation of the invention is presented herein for the purpose of exemplification, but it will be understood that the invention is capable of being practiced or utilized in other modified forms which come equally within the scope of the appended claims, wherefore the drawings and description are to be taken in an illustrative and not in an unnecessarily limiting 35 sense.

In the accompanying drawings,

35 Fig. 1 shows in vertical longitudinal section one end of a refrigerator car illustrating the tanks filled with ice as in the initial stage of treatment in accordance with the present invention;

40 Fig. 2 is a similar view illustrating the iced tanks filled with a low temperature cooling agent designed to cooperate with the ice in the further practice of the method;

45 Fig. 3 is intended to illustrate the condition of

the ice in the tanks after a period of time has elapsed and a portion of the ice has melted;

5 Fig. 4 is a transverse section through one end of the car and the battery of ice tanks at that end.

The cooling agents which are preferred for use in practicing the herein described method comprise crushed ice and salt to which is added a brine, but pre-frozen eutectic mixtures, such as slush brine or ribbon ice, without the subsequent 10 addition of any liquid, may be employed, as may also any other medium adapted for the purpose.

Referring to the drawings, the wall of the refrigerator car is shown at 11, the floor at 12, and the roof at 13. Within each end of the car is 15 arranged the usual battery of ice tanks 14, which tanks may be provided adjacent their lower ends, or at any other suitable points, with properly controlled outlets for draining the same. The tanks 14 in ordinary practice are supplied with ice from 20 above through openings which are provided with hatches 15. The tanks are separated in the usual manner from the lading space of the car by a protective bulkhead 16. This bulkhead preferably is spaced from the ceiling and floor of the 25 car, so as to function as an air-guiding baffle which is effective to permit the warm air in the car to move into contact with the tanks at the top of the car, and thereafter retain the air in intimate association with the exterior surfaces of the 30 tanks to effect its cooling, as a result of which the cooled air moves downwardly by gravity and returns to the lading space by moving outwardly away from the tanks below the bulkhead. A tray 17 is located below the tanks 14 for preventing any 35 discharge from the interior and condensation from the exterior of the tanks running back into the car interior. This drip tray is provided with an outlet pipe 18 which extends down through the floor of the car. The construction thus far de- 40 scribed is that which is found in many present day refrigerator cars of approved design. The present invention may be practiced advantageously with a car of this type, but it is not limited in its application and may be used with 45 other cars of somewhat different types.

As indicated in Fig. 1, the tanks initially are charged with crushed ice 19 by being filled with the same, a suitable percentage of salt being added to the ice. To the ice is added also a brine, 50 as appears in Fig. 2, designated by the numeral 20, and the quantity of the brine so added is such as to cover completely the ice within the tanks. By adding the brine in the quantity and manner referred to marked advantages result in 55

that a cooling surface on the tanks equivalent to practically the entire surface thereof is continuously maintained, as distinguished from the effect of ice and salt mixtures ordinarily employed. In the latter, as the ice melts it decreases in volume and the cooling surface is thereby decreased but in a greater proportion than the decrease in the weight of ice by reason of the remaining ice having melted away from intimate contact with the tank walls and assuming a pyramidal shape creating an air space between the ice and the walls, and thus reducing the effective cooling surface. For example, it might be said that when the ice is dissipated to the extent of 50%, the effective cooling surface of the tanks may be reduced 60% to 70%. By the addition of the brine, however, when the ice is dissipated to the extent of 50% the cooling surface still remains the same as at the start by reason of the remaining ice floating on the top of the brine, which condition is illustrated in Fig. 3, and the natural convection currents set up in the brine beneath the ice acting with the ice to maintain the mixture at a continuous low temperature. It follows, therefore, that the walls of the tanks 14 present, in their entirety, chilled surfaces to the air within the car, and that the air, by convection, circulates throughout the interior of the car and reduces the temperature thereof to the desired point for the attainment of the chilling conditions that are sought. In such circulation the air currents pass through the opening at the top of the bulkhead 16 and flow downwardly between the bulkhead and the outer walls of the tanks. Upon reaching the floor of the car about the tanks the cooled air will move back into the car interior along the floor and walls. As the air passes over the walls and floor it extracts heat which increases the temperature of the circulating air and causes it to rise and establish convection currents within the car. These currents act to carry the heated air along the roof of the car towards the opening between the bulkhead and the tanks and thereby complete the cycle.

The filling of the tanks with the ice constitutes the charging stage of the herein described method and imparts an initial lowering of the temperature of the tanks. When the brining stage follows, as when the tanks are filled with the brine to cover completely the ice introduced in the charging stage, there is created a material reduction in the temperature of the tanks. The melting of the ice induces further reduction in the temperature of the mixture, and during such melting the ice floats in the brine to the top thereof, as indicated in Fig. 3. But the entire liquid body within the tanks is effective to maintain the low temperature of the tanks, and the entire surface of the latter thereby is exposed for contact by the convective air currents in their circulation. This attains a degree of refrigeration that is greatly increased over the methods now commonly employed, and the period of effective refrigeration likewise is prolonged. Due to the large expanse of contact surface of the tanks the air within the car is more uniformly treated and the refrigerating agent utilized to greater advantage than in the present methods. The air within the car will circulate between and around the articles of lading and over the surfaces of the tanks, thereby maintaining the desired low temperature until the charge of ice within the tanks has become depleted.

To illustrate the advantages and novelty of

this invention the results of some actual shipments of fresh meats following the methods as outlined above are cited. In one case cars were shipped from Chicago to New York in summer and unloaded at the destination after a total elapsed time, from the time the car was closed at the loading dock until it was unloaded, of from 95 to 120 hours. The product arrived in good condition. The cars had internal temperatures of 34° to 36° F. when opened for loading, and throughout the entire journey the temperature increase was held to a maximum of 6° to 8° without any re-icing of the cars in transit, whereas the usual practice in handling cars required that the cars be re-iced at four stations enroute and once at the destination. In this case the average outdoor temperature during the run was 79.5° with a maximum of 105.0° F.

In another case, a shipment of cars loaded with fresh meats was made from Omaha to New York without any re-icing in transit during which run the average outdoor temperature was 84.6° with a maximum of 110° F. without any re-icing after leaving the shipping point. All product unloaded in good condition at car temperatures ranging from 41° to 43° F., which represents a car interior temperature rise of 6° to 8°. The elapsed time from loading to unloading was from 85 to 95 hours. The re-icings required in transit by cars shipped in the same train but prepared in the usual manner amounted to five, which in the case of the specially prepared cars were entirely eliminated.

With cars shipped by the method of the present invention a gradual rise in interior temperature is experienced. Over the range of temperatures indicated this rise in temperature does no harm to the product in the car. In cars shipped by the usual methods of refrigeration, after each icing a more or less rapid rise in temperature is experienced, up to the time of the next re-icing. The re-icing causes the temperature to fall, thus starting up a cycle of temperature variations, each subsequent re-icing representing a cycle. Although the temperature variation range may be no greater than the total temperature rise of the specially prepared cars, the continued repetition of temperature variations adversely affects the product. This damaging influence is not present in cars refrigerated in accordance with the present invention as their temperature rise is through one cycle only.

While the invention has been described in its application to refrigerator cars, it is obvious that the same is adaptable to automobile refrigerator trucks without departing from the essential characteristics of the invention in its application to refrigerator cars, and it is to be understood that such extended application is within the purview of the invention.

As an alternative arrangement for obtaining the desired low temperature area exposed for contact by the air currents, the level of the outlets of the tanks 14 may be such that the space in the tanks below that level will contain sufficient brine that the displacement of the ice, when added, will raise the brine level to such a point as to give an inside wetted surface equal to or closely approaching the area of wetted surface that is obtained by adding brine to the tanks after they are iced, as shown in Fig. 2.

My invention further contemplates the pre-cooling or conditioning of refrigerator cars by the provision of a low temperature refrigerant maintaining a wetted cooling surface on the tanks

equivalent substantially to the entire surface thereof. To this end, brine or other low temperature refrigerant may be provided in the tanks in quantity sufficient to cover the charge of ice and salt, or pre-frozen eutectic mixtures such as 5 slush brine or ribbon ice may be employed without the subsequent addition of any liquid, whereby the walls of the tanks are continuously maintained over substantially the entire area at a 10 reduced temperature and present a maximum surface for the absorption of heat from the car interior. As a specific example of such pre-cooling, the tanks may first be charged with ice and salt or other meltable refrigerant, as in Fig. 15 1, and may then be filled with brine or other non-freezing liquid completely covering the ice or meltable refrigerant as in Fig. 2. During the cooling of the car, if ice is used, the ice melts and floats in the upper portion of the brine or 20 other non-freezing liquid, as indicated in Fig. 3, the effective cooling area of the tank wells, however, being maintained undiminished due to the continuous contact of the brine therewith; the natural convection currents set up in the brine 25 or other non-freezing liquid beneath the ice or other meltable refrigerant, moreover, coating with the ice to maintain the mixture at a continuous low temperature, and the brine or other non-freezing liquid filling the voids between the 30 ice and the tank walls and providing for uninterrupted transmission of heat from the car through said walls and to said ice or to the meltable refrigerant. After the desired pre-chilling has been attained, the tanks may be replenished 35 as desired; to which end the brine or other non-freezing liquid may be withdrawn from the tanks until only sufficient brine or other non-freezing liquid remains in the tanks to completely fill the voids between the ice or other meltable refrigerant particles when the tanks are subsequently recharged with ice or other meltable refrigerant as required to replace the ice or other meltable refrigerant melted during the pre-cooling period. Pre-cooling in the manner hereinbefore described may be accomplished with 40 marked efficiency and in substantially shorter periods than in prior practice, owing to the maintenance of a continuously cool surface on the tank walls and to the elimination of air gaps between the interior surfaces of said walls and the refrigerant in the tanks.

Although the procedure recited in the foregoing description provides for first charging the tanks with ice and salt or other meltable refrigerant and then adding brine or other non-freezing liquid, my process contemplates that in some instances it might be desirable to reverse the procedure by first charging the tanks with the brine or other non-freezing liquid and finally 55 fully charging the tanks with ice and salt or other meltable refrigerant. In either instance the tanks will contain the full capacity of ice and salt or other meltable refrigerant plus the brine or other non-freezing liquid necessary to fill the voids between the ice or other meltable refrigerant particles.

Summarizing the present invention, it provides a method for refrigerating cars, whether for transit or for pre-cooling the same for transit, 60 by incorporating into the tanks a charge of ice, salt and preformed low temperature liquid sufficient to cover the ice completely; or by charging the tanks with a preformed eutectic mixture, such as slush brine or ribbon ice, without the addition of any liquid. A cooling surface equiva-

lent to substantially the entire area of the surface of the tanks is thereby maintained and gaps or interstices occurring between unmelted particles of the meltable refrigerant in the tanks are filled with the low temperature liquid, whereby 5 heat from the car interior may be continuously and efficiently transmitted through the tank walls to the refrigerant without interruption by the presence of air gaps between the tank walls and the refrigerant particles.

10

I claim:

1. The method of refrigerating cars, which consists in charging the cooling tanks thereof with a quantum of ice, adding thereto a heat transmitting liquid, and maintaining flotation of 15 the ice within the tanks during meltage without diminishing the volume of the liquid contents of the tanks, whereby to maintain a cooling surface on the tanks equivalent to substantially the entire surface thereof.

20

2. The method of refrigerating cars, which consists in charging the cooling tanks thereof with a quantum of ice, adding thereto a low temperature liquid in sufficient volume to cover the ice in the tanks and thereby reduce the temperature 25 of the walls of the tanks, and maintaining flotation of the ice within the tanks during meltage without diminishing the volume of the liquid contents of the tanks, whereby to induce convective currents in the liquid and maintain a cooling 30 surface on the tanks equivalent to substantially the entire surface thereof.

25

3. The method of refrigerating cars, which consists in charging the tanks thereof with the ice or other refrigerant used, then filling the 35 charged tanks with a low temperature liquid, and maintaining flotation of the ice or other refrigerant within the tanks during meltage without diminishing the volume of the liquid contents of the tanks, whereby to maintain a cooling surface 40 on the tanks equivalent to substantially the entire surface thereof.

35

4. The method of refrigerating cars, which consists in charging the cooling tanks thereof with a quantum of ice, adding thereto a liquid, and 45 maintaining flotation of the ice within the tanks during meltage without diminishing the volume of the liquid contents of the tanks, thereby to maintain a cooling surface on the tanks equivalent to substantially the entire surface thereof.

50

5. The method of refrigerating cars, which comprises introducing into the cooling tanks thereof a cooling liquid of sufficiently low temperature to impart to the walls of the tanks a desired reduced temperature, and maintaining 55 the liquid contents of the tanks at reduced temperature to maintain a cooling surface on the tanks equivalent to substantially the entire surface thereof.

55

6. The method of refrigerating cars, which 60 comprises charging a tank thereof with a meltable refrigerant and maintaining in a wetted condition substantially the entire inner area of a wall of said tank during the melting of said refrigerant.

65

7. The method of refrigerating cars, which comprises charging a tank thereof with a meltable refrigerant and maintaining a heat transmitting liquid in such volume to occupy during 70 melting of said refrigerant substantially all spaces between the unmelted refrigerant and the wall of said tank for continuously transmitting heat from said car to the unmelted refrigerant, meanwhile maintaining flotation of the unmelted refrigerant.

75

ant in said tank without decrease in volume of the tank contents.

8. The method of refrigerating cars, which comprises charging a tank thereof with a melt-
5 able refrigerant and maintaining a heat trans-
mitting liquid in said tank in volume sufficient
to provide a continuously wetted surface over
substantially the entire area of a wall of said
10 tank during the melting of said refrigerant and
to preclude the formation of air gaps between
unmelted refrigerant and the inner walls of said
tank during melting of said refrigerant.

9. The method of refrigerating cars, which
15 comprises charging a tank thereof with a meltable
refrigerant and maintaining in said tank during
melting thereof a low temperature liquid in con-
tact with a wall of said tank to a height sub-
stantially equal to that of the highest unmelted
20 refrigerant in said tank, meanwhile maintaining
floatation of the unmelted refrigerant in said tank
without decrease in volume of the tank contents.

10. The method of refrigerating cars, which
comprises charging a tank thereof with a melt-
able refrigerant and adding thereto a preformed
25 low temperature liquid to maintain a continuous-
ly wetted cold surface on the interior of said
tank during melting of said meltable refrigerant.

11. The method of refrigerating cars, which
30 comprises charging a tank thereof with a melt-
able solid refrigerant and adding thereto a pre-
formed low temperature liquid in volume suffi-
cient to preclude the formation of air gaps be-
tween the solid refrigerant and the interior walls
35 of said tank during melting of said solid refrig-
erant.

12. The method of refrigerating cars, which
comprises charging a tank thereof with a melt-
able solid refrigerant and adding thereto a pre-
formed low temperature liquid in volume suffi-
40 cient to substantially cover said solid refrigerant
and to maintain a continuously wetted surface
over substantially the entire inner area of a wall
of said tank during melting of said solid refrig-
erant.

13. The method of refrigerating cars, which
45 comprises charging a tank thereof with ice and
adding thereto a preformed liquid of such char-
acter and in such volume as to continuously trans-
mit heat from the car to said ice despite melting
50 of the ice out of contact with the walls of said
tank.

14. The method of refrigerating cars, which
comprises charging a tank thereof with ice and
55 maintaining in said tank a low temperature liquid
formed prior to the insertion of said ice in such
volume as to substantially fill all spaces between
the unmelted ice and the walls of said tank during
melting of said ice and thereby to transmit heat
from the car to said ice.

15. The method of refrigerating cars, which
60 comprises charging a tank thereof with ice and
salt, and also with a low temperature liquid of
sufficient volume to fill substantially all gaps be-
tween the ice and the walls of said tank during
melting of said ice and thereby to transmit heat
continuously from said car to said ice.

16. The method of refrigerating cars, which
comprises charging a tank thereof with ice and
salt and also with a low temperature liquid in
70 volume sufficient to substantially completely cover
said ice.

17. The method of refrigerating cars, which
comprises providing in a tank thereof a low
temperature liquid and thereafter inserting there-
75 in a meltable refrigerant, the quantities of said

liquid and said refrigerant being such that the
introduction of said refrigerant causes said liquid
to rise sufficiently to fill substantially all spaces
between said refrigerant and the walls of said
tank during melting of said refrigerant.

18. The method of refrigerating cars, which
comprises providing in a tank thereof a low tem-
perature liquid and thereafter inserting therein
a meltable refrigerant, the quantities of said
liquid and said refrigerant being such that the 10
introduction of said refrigerant causes said liquid
to rise to such extent as to maintain on an inner
surface of a wall of said tank during melting
of said refrigerant a wetted area of a height sub-
stantially equal to the maximum distance of any 15
part of said refrigerant from the bottom of said
tank.

19. The method of refrigerating cars, which
comprises charging a tank thereof with a melt-
able refrigerant and also with a low temperature 20
liquid of such quantity as to maintain contact
with the inner surface of a wall of said tank
over substantially the entire area thereof through-
out melting of said refrigerant.

20. The method of refrigerating cars, which
25 consists in charging the cooling tanks thereof
with a quantum of ice, providing therein a low
temperature liquid formed independently of said
ice to reduce the temperature of the walls of the
tanks, and maintaining floatation of the ice within 30
the tanks during meltage without diminishing the
volume of the liquid contents of the tanks, whereby
to maintain a cooling surface on the tanks
equivalent to substantially the entire surface
thereof.

21. The method of refrigerating cars, which
consists in charging the cooling tanks thereof
with a quantum of ice, providing therein a low
temperature liquid formed independently of said
ice in sufficient volume to cover the ice in the 40
tanks and thereby reduce the temperature of the
walls of the tanks, and maintaining floatation
of the ice within the tanks during meltage without
diminishing the volume of the liquid contents
of the tanks, whereby to induce convective cur-
rents in the liquid and maintain a cooling surface
45 on the tanks equivalent to substantially the entire
surface thereof.

22. The method of refrigerating cars, which
50 consists in charging the cooling tanks thereof
with a quantum of ice, adding thereto a low tem-
perature liquid to reduce the temperature of the
walls of the tanks, and maintaining floatation of
the ice within the tanks during meltage without
55 diminishing the volume of the liquid contents of
the tanks, whereby to maintain a cooling sur-
face on the tanks equivalent to substantially the
entire surface thereof.

23. The method of refrigerating cars, which
60 consists in charging the cooling tanks thereof
with a quantum of ice, adding thereto a low tem-
perature liquid in sufficient volume to cover the
ice in the tanks, and thereby to reduce the tem-
perature of the walls of the tanks, maintaining
floatation of the ice within the tanks during melt-
65 age without diminishing the volume of the liquid
contents of the tanks, whereby to induce con-
vective currents in the liquid and maintain a
cooling surface on the tanks equivalent to sub-
stantially the entire surface thereof, then remov-
ing a predetermined volume of the liquid contents
of the tanks, and re-icing the tanks to the ex-
tent required for filling the same.

24. The method of refrigerating cars, which
75 consists in charging the cooling tanks thereof

- with a quantum of ice, adding thereto, a low temperature liquid in sufficient volume to cover the ice in the tanks, and thereby to reduce the temperature of the walls of the tanks, maintaining flotation of the ice within the tanks during meltage without diminishing the volume of the liquid contents of the tanks, whereby to induce convective currents in the liquid and maintain a cooling surface on the tanks equivalent to substantially the entire surface thereof, then removing a portion of the liquid contents of the tanks, and re-icing the tanks to the extent required for filling the same.
25. A cooling unit for use in a refrigerator car, consisting of a refrigerant tank or container adapted to be located in the end of a car, said tank having a refrigerant therein, and a liquid surrounding the refrigerant in sufficient quantity to fill all voids in the refrigerant mass and to substantially fill said tank.
26. A cooling unit for use in a refrigerator car,
- 5 consisting of a refrigerant tank or container adapted to be located in the end of a car, said tank having a solid refrigerant therein, and a liquid surrounding the solid refrigerant in sufficient quantity to fill all voids in the refrigerant mass and to substantially fill said tank.
- 10 27. A cooling unit for use in a refrigerator car, consisting of a refrigerant tank or container adapted to be located in the end of a car, said tank having a charge of ice therein, and a liquid surrounding the ice in sufficient quantity to fill all voids in the ice mass and to substantially fill said tank.
- 15 28. A cooling unit for use in a refrigerator car, consisting of a refrigerant tank or container adapted to be located in the end of a car, said tank having therein a charge of broken ice, and a quantity of brine sufficient to fill all voids between the ice fragments and to substantially fill said tank.

DAVID P. MINARD.
